CONTAINER FOR ASPHALT AND THE LIKE

Peter Santina, San Francisco, Calif.

Application March 24, 1949, Serial No. 83,232

5 Claims. (Cl. 220—49)

1

This invention relates to a metal container for asphalt and the like. More particularly, it relates to a metallic container or barrel formed with the usual sideseam and having means for ripping open the sideseam so as to allow access to the contents of the container.

In packaging asphalt it is common practice to provide a cylindrical metallic container or barrel having a bottom closure and open at the top. The asphalt exists in the container in the form of a cylindrical block, and at the point of use it is essential either to heat the container to melt the asphalt so that it may flow from the container, to chop out the solid contents of the container, or to rip open the container to provide access to the solid block of asphalt.

The various means previously employed for removing asphalt from such containers have been unsatisfactory. Heating is obviously undesirable, especially at small installations. Thus, a source of heat must be provided, and also means for handling the hot containers and the hot fluid asphalt. Time must be allowed to melt the asphalt.

Chopping the asphalt out of a container is obviously laborious, and prior methods of ripping the container have also been laborious and have damaged the container excessively.

It is an object of the present invention to provide improved means for opening metallic containers of the character described.

It is a particular object of the invention to provide a means for opening metallic containers containing asphalt, such means being embodied in the container and immediately available whenever desired to open the container.

It is a further and particular object of the invention to provide a simple and effective means for opening a metallic container containing asphalt or the like, such means being effective to part the container at its sideseam while at the same time doing a minimum of damage to the container.

These and other objects of the invention will be apparent from the ensuing description and the appended claims.

Certain forms which the invention may assume are exemplified in the following description and illustrated by way of example in the accompanying drawings, in which:

Fig. 1 is a perspective view of one embodiment of the invention.

Fig. 2 is a section taken along the line 2—2 of Fig. 1.

2

Fig. 3 is a section taken along the line 3—3 of Fig. 1.

Fig. 4 is a perspective view of another embodiment of the invention.

Fig. 5 is a section taken along the line 5—5 of Fig. 4.

Referring now to the drawings, and more particularly to Figs. 1, 2 and 3, there is shown a cylindrical metallic container or barrel 10 having a body 11 preferably constructed of a light gauge metal such as a light gauge aluminum alloy. The body is provided with a bottom closure 12. The container is shown as being filled with a solid material 13, such as asphalt. The usual sideseam 14 and double end seam 15 are provided. Referring more particularly to Figs. 2 and 3, as illustrated, the sideseams 14 comprise an inner hook 16 and an outer hook 17 which is interlocked with the inner hook. The double end seam comprises an inner hook 18 and an outer hook 19 which is interlocked with the inner hook.

The container 10 embodies a wire rip cord 25 which, as illustrated, is seated in the bend of the outer hook 17 of the sideseam 14. At its ends the wire rip cord 25 is formed into a loop 26 or 27. As shown in Fig. 3 the rip cord is also seated in the double end seam 15 and it has the same general configuration as the outer hook 19. The wire 25 is preferably a piano wire or other wire having a comparable high tensile strength.

In manufacturing the container 10 the usual procedure is involved. That is, the body blanks are formed and notched and hooks are formed for forming the sideseam and a flange is formed for forming the end seam. The ends are also formed with flanges for the end seam. The only respect in which usual can forming operations are modified is that the rip cord 25 is inserted in the outer hook 17 before the latter is interlocked with the inner hook 16.

When it is desired to remove the asphalt 13 from the container, the upper loop 26 of the rip cord 25 is grasped by hand or with a tool such as a pair of pliers and is pulled laterally and downwardly as indicated by the arrow *a* in Fig. 1. The wire thereby cuts the outer hook 17 at its bend or crease which, of course, is the weakest point in the seam. The sideseam 14 is thus effectively ripped. To remove the bottom closure 12, the bottom loop 27 will be pulled upwardly to interlock the double seam 15. It is then a simple operation to peel the body 11 and the bottom closure 12 from the solid block of asphalt 13.

Referring now to Figs. 4 and 5, the container 10 there shown is identical with that illustrated in Fig. 1 and described hereinabove except that it is provided with a lid 28 which may be secured to the body 11 by means of a double seam 29 or by any other suitable means. As also illustrated, near its top and bottom, the body 11 is slotted to provide annular top and bottom grooves 30 or 31. The rip cord 25, having end loops 26 and 27, is disposed in the sideseam 14 and projects 10 outwardly from the end seams 15 and 29 in the manner described hereinabove and illustrated in Figs. 2 and 3.

In this embodiment of the invention the rip cord 25 may be manipulated as described above. However, it is not necessary to rip off both end closures. Thus, the rip cord 25 may be pulled downwardly until it rips the body 11 between the upper and lower annular grooves 30 and 31. These grooves so weaken the body 11 that, after 15 it has been ripped between the grooves 30 and 31, it is a simple matter to peel the central portion 32 of the body 11 from the block of asphalt. Thus, access is provided to the asphalt without ripping off the bottom closure.

This embodiment of the invention is especially adapted to containers in which the bottom closure, the top closure or both end closures are clamped to the body of the container by means such that a rip cord will not remove them. Thus, it is necessary to extend the rip cord only from the top groove 30 to the bottom groove 31.

It will be apparent that a novel and very useful means for opening a metallic container or barrel is provided. Such means is inexpensive, involving no modification of the usual seam forming operations in forming a container except to place a small length of wire in the outer hook of the sideseams before forming the seam. Operation of the device is extremely simple, and may be carried out manually or by means of a simple tool such as a pair of pliers. A further and important advantage resides in the fact that the body 11 of the container is damaged only to the extent that the inner portion of the outer hook is ripped loose from the main body of the container. This constitutes a very small fraction of the container. The body 11, after cleaning, can be used again to form a container having practically the same volume.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is—

1. A metallic container having a tubular body portion including a sideseam formed of interlocked inner and outer hooks, an end closure for said container locked to the body portion by means of an end seam, and a rip cord seated in the bend of said outer hook and also seated in said end seam, one end of said rip cord pro-

jecting outwardly from the container to provide a hand hold.

5 2. A metallic container comprising a tubular body having a side seam, a rip cord mounted within said seam and extending longitudinally thereof and beyond at least one end of the body and a cover at the end of the body from which said end of said rip cord extends, said cord being returned bent by said cover and extending between said cover and said body.

10 3. A metallic container comprising a tubular body having a side seam, a rip cord mounted within said seam and extending longitudinally thereof and beyond at least one end of the body and a cover at the end of the body from which said end of said rip cord extends, said cord being returned bent by said cover and extending between said cover and said body, and a pull ring formed on the extended end of said rip cord.

15 4. A metallic container comprising a tubular body having a side seam, a rip cord mounted within said seam and extending longitudinally thereof and beyond both ends of said body and a cover at both ends of the body the extended 20 ends of said cord being returned bent by said covers and extending between said covers and said body.

25 5. In a can having a longitudinally extending side seam formed by interlocking return bent edges of the can body, a rip cord mounted within 30 said side seam and extending beyond both ends thereof, a pair of spaced annular weakenings in the can body adjacent the ends thereof, a pair of cap-like covers engaging over the both 35 ends of said body, the ends of said rip cord being returned bent under the edges of said covers and extending therebeyond and a pair of pull rings formed on the extended ends of said rip cord.

40 PETER SANTINA.
